UNITED STATES PATENT OFFICE.

DAVID E. COOL, OF ST. LOUIS, MISSOURI, ASSIGNOR, BY MESNE ASSIGNMENTS, TO NORWAY WELT PATENTS TRUST, A TRUST ESTATE.

MACHINE FOR OPERATING ON SOLES.

Application filed March 25, 1921. Serial No. 455,508.

This invention relates to machines for operating on soles and more particularly for providing the margin of a sole, such as an insole, with an edge adapted to permit attachment thereto of an upper.

One of the objects of this invention is to provide a machine in which the operations on the sole by the tool and the feed thereof by the feeding instrumentalities are so accomplished as to obviate marring of the sole.

Another object of this invention is to provide a machine which, while operating to cut from the margin of the sole a strip and provide an overhanging shoulder to which the upper can be attached, is so constructed as to feed the sole by engagement therewith at the margin and that portion which is subsequently cut off so as to prevent marring of the finished sole.

Further objects will appear from the detail description taken in connection with the accompanying drawing, in which:

Figure 1 is a detail front elevation of a machine embodying this invention;

Figure 2 is a detail side elevation;

Figure 3 is a detail rear elevation;

Figure 4 is a detail section on the line 4—4, Figure 3;

Figure 5 is an enlarged section showing the operation of the tool;

Figure 6 is a detail perspective view showing the different parts of the mechanism; and

Figure 7 is a detail showing the sole.

Referring to the accompanying drawing, and more particularly to Figure 7, the insole 1, as shown, has a wing 2 thereon with an overhanging shoulder 3 arranged above but inside of the wing. This sole is formed by slitting the sole edge therealong on the line 4, thereby forming a lip 5, and by severing the lip by a cut taken along but inside of the sole margin but at an acute angle so as to form the overhanging shoulder 3.

Referring to Figure 5 and 6, the slit 4 is formed by a slitting knife 6 which bevels laterally and from front to rear as shown, while the angular shoulder 3 is formed by a sole face cutter 7 having a downwardly and laterally extending point which intersects the point of the slitting knife; the cutting edge of the slitting knife is, however, arranged in advance of the cutting edge of the

sole face cutter 7 so that the slit will be completely formed before the cut extending into the slit is taken; accordingly, these two cutters combine to sever from the sole edge, the strip 5.

In the illustrated embodiment of this invention, the slitting knife and cutter are mounted on a carrier which in turn is mounted for movement forwardly and backwardly over a work support, on which the sole is mounted with its inside face arranged uppermost. Cooperating with the sole is a presser-gage which holds the sole down on the table, a sole edge gage which positions the sole laterally, and a presser-foot or work retainer which is adapted to engage the sole and which is arranged for vertical movement with the sole so as to clamp the same on the work support and then release the same. While the sole is clamped by the presser-foot the slitting knife and cutter move forwardly with their carrier and the presser-gage attached thereto so as to take a short cut; after the knife and cutter come to rest, the presser-foot is raised to release the work and then the knife and cutter move rearwardly with the carrier thereby feeding the work; the presser-foot then again engages the work and the operations are repeated.

Referring now to Figures 1 to 6 inclusive, 10 designates a machine head which has mounted thereon a carrier 11 which is arranged for movement back and forth. The frame has mounted therein a presser-foot 12 which is mounted for vertical movement so as to engage and disengage the sole which is mounted on a suitable work table 13. A suitable edge-gage 14 is provided which is arranged for lateral adjustment to provide for various extensions. A presser-gage 15 is mounted on the carrier 11 and is arranged to extend down to the upper face of the sole. The slitting knife 6 is clamped on a shank 16 by screws 160 which shank, in turn, is adjustably mounted on the carrier 11, being adjusted by a screw 17. The parts so far described may, in a general way, be of the construction as shown in the United States Patent No. 1,023,801, dated April 23, 1912. As in the machine of the patent, the carrier 11 is moved back and forth in timed relation with the movement of the presser-foot 12 by

suitable mechanism operated from the power shaft, but not shown.

The slitting knife 6 is mounted on the movable carrier 11, and also mounted on this carrier and clamped to a lug 18 thereon (on the opposite side of which is also clamped the presser-gage 15) is a bracket 19 on which is adjustably mounted the cutter 7, the adjustable mounting being through a screw 20 engaging a slot in the cutter and threaded into the bracket 19. The presser-gage 15 has a foot 21 which extends over the margin of the sole supported on the table and slightly beyond the tip of the slitting knife. The presser-foot 12 has a foot 22 which extends over the margin of the sole and inwardly for some distance beyond the presser-foot 21 and the knife and cutter, and this presser-foot has a roughened portion 23 arranged between the tips of the knife and cutter and the margin of the sole. The presser-foot further has a lug 24 arranged to extend into a slot 25 in the presser-foot when they come together. During the operation of the machine and assuming the presser-foot to be down to clamp the sole on the table as the carrier 11 moves forwardly carrying the knife and cutter with it, the slitting knife will operate in advance of the cutter to slit the sole while the cutter will sever the strip or lip 5 and form the shoulder 3; as the carrier comes to rest, the presser-foot will be raised and the carrier will then shift carrying the sole with it and feeding the same; the presser-foot then again comes down on the sole to retain the same and the operation is repeated. It will be noted that the roughened portion 23 of the presser-foot engages that part of portion of the sole margin which is subsequently cut off; accordingly, the inner face of the insole is not marred but left smooth. Both the slitting knife and the cutter can be adjusted by manipulation of the screws 17, 20 and 160, while both the knife and the cutter can be removed to permit grinding of the same.

It is obvious that various changes may be made in the details of construction without departing from the spirit of this invention; it is, therefore, to be understood that this invention is not to be limited to the specific details shown and described.

Having thus described the invention, what is claimed is:

1. A machine for operating on soles, comprising, means for slitting the sole edge therealong, means for cutting the sole face along but inside of the sole margin so as to intersect the slit, means for moving said slitting and cutting means, means cooperating with said slitting and cutting means for intermittently feeding the sole, and an element engaging the sole marginally outside of the cut to be subsequently made by said cutting

means and holding the sole stationary during the pauses in the feed.

2. A machine for operating on soles, comprising, means for slitting the sole edge therealong, means for cutting the sole face along but inside of the sole margin so as to intersect the slit, means for moving said slitting and cutting means in one direction to slit and cut the sole and in the other direction to feed the sole, and means for retaining the sole marginally outside of the cut to be subsequently made by said cutting means. 75

3. A machine for operating on soles, comprising, means for slitting the sole edge therealong, means for cutting the sole face along but inside of the sole margin so as to intersect the slit, and means for retaining the sole marginally outside of the cut to be subsequently made by said cutting means. 80

4. A machine for operating on soles, comprising, means for cutting off a strip from and along the sole margin, feeding means cooperating with said cutting means, and a retaining element engaging the sole at its margin transversely coextensive with the strip to be subsequently cut therefrom. 90

5. A machine for operating on soles, comprising, means for cutting off a strip from and along the sole margin, feeding means cooperating with said cutting means, and a retaining element engaging the sole at its margin transversely coextensive with and in advance of the strip which is subsequently cut off. 95

6. A machine for operating on soles, comprising, means for cutting off a strip from and along the sole margin, feeding means cooperating with said cutting means, and a retaining element engaging the sole portion which is subsequently cut off. 100

7. A machine for operating on soles, comprising, means for cutting off a strip from and along the sole margin to sever said strip from the sole, and a presser gage extending over the sole margin and engaging the portion to be subsequently severed. 110

8. A machine for operating on soles, comprising, means for cutting off a strip from and along the sole margin, and a presser-foot having a retaining part engaging the portion to be subsequently severed and transversely coextensive with the strip to be subsequently cut therefrom. 115

9. A machine for operating on soles, comprising, means for cutting off a strip from and along the sole margin, and a presser-foot having a retaining part engaging the sole portion which is to be subsequently cut off and having a portion extending further over the sole. 120

10. A machine for operating on soles, comprising, means for cutting off a strip from and along the sole margin, a presser gage extending over the sole margin, and a 130

presser-foot having a retaining part engaging the sole at its margin transversely coextensive with the strip to be subsequently cut therefrom.

5 11. A machine for operating on soles, comprising, means for cutting off a strip from and along the sole margin, a presser

gage extending over the sole margin, means for feeding the sole through the medium of said cutting means, and means for retaining the sole at its margin. 10

In testimony whereof I affix my signature this 30th day of September, 1920.

DAVID E. COOL.
